UMBRELLA FASTENING MEANS FOR BAGS

Filed Jan. 2, 1929

UNITED STATES PATENT OFFICE

JOSEPH R. DANNER, OF WILMAR, CALIFORNIA

UMBRELLA-FASTENING MEANS FOR BAGS

Application filed January 2, 1929. Serial No. 329,887.

This invention relates to improvements in brackets and more particularly to means for securing umbrellas or parasols upon the bags of letter carriers or postmen.

One of the objects of my invention is to provide simple, efficient and inexpensive means designed for the purpose of attaching in convenient manner an umbrella to the letter carrier's letter bag so that the hands of the postman may be free to distribute and to examine mail.

It is well known that in inclement weather as when it rains, snows or hails the letter carrier goes about his daily task out in the open streets subjecting himself and the bag to the action of the elements. Besides causing annoyance and damage to the contents of the mail bag this tends to destroy the efficiency of the letter carrier as he makes his rounds. My invention aims to secure an umbrella in position upon the mail bag so the covering of the umbrella will extend over the head and shoulders of the postman, sheltering him against the wind, rain, and storm, and protecting the contents of the mail bag from water. Today many postmen carry an umbrella about with them in making calls, thus necessitating carrying the umbrella in one hand, leaving the other hand alone free for work.

Another object of my invention is to provide improved means for instantly securing an umbrella handle in rigid erect position upon a mail bag, as the bag is held suspended upon the shoulder of the postman, the umbrella handle projecting upwardly of the bag leaving the postman's arm free and outside of the umbrella handle.

A still further object of my invention is to provide a device with a clamping member for straddling a bag side with set screws for securing the device upon the bag, and with a post to which the umbrella handle fits in telescoping relation and by which it is latched in position against displacement.

With the above and other objects in view my invention consists in the combination, arrangement and details of construction disclosed in the drawings and specifications, and then more particularly pointed out in the appended claims.

In the drawings, wherein similar reference characters designate similar parts throughout the respective views,

Figure 1 is a vertical sectional elevation of the parts of my invention,

Figure 2 is a side elevation of my invention,

Figure 3 is a vertical elevation of my invention looking from the rear,

Figure 4 is a vertical elevation, partly in section, showing the device attached to a bag, shown in section,

Figure 5 is a fragmental detail view of my invention showing the front edge of the latching post,

Figure 6 is a top plan view of my invention,

Figure 7 is a bottom plan view of my invention, and Figure 8 shows the device attached to the mail carrier's bag. Referring to the drawings, which are merely illustrative of my invention the parts of my invention are disclosed. It will be clearly seen that the device consists of a clamping member horseshoe shaped in contour having the parallel arms or stems 10 and 11 connected together by the bight 12 to which is soldered as at 13 an upwardly extending or rising stick or post 13 which is formed tubular inside so as to have the internal bore 21. As a means of

locking the clamping member frictionally and rigidly to one side of a leather or canvas bag, such as is in use by letter carriers, set screws or like members 24 are tapped

threadedly at right angles into one arm 11 of the clamping member so that by turning their handles or heads 25 these screw shanks 24 can be adjustably moved in the space between arms 10 and 11 to engage the bag side A, while

arm 10 engages the other face of this same bag

side. Any other clamping means may be employed which can form an under support for the umbrella latching stick or post 13.

It will be understood that the umbrella or parasol to be used in conjunction with the post 13 will be of such a form that the lower terminal of its handle will be tubular as at 16 so that this tubular handle may be fitted in telescopic fashion and relation upon the 10 stick or post 13 and pushed down as far as it will go. At the lower end of this tubular handle 16 is formed a slit or slot 17, and at its upper end there is snugly fitted the rod 15 leading to the umbrella frame as is well 15 understood, the umbrella covering being designated C (Figure 7).

Located in the tubular post 13 is a latching member consisting of a leaf or sear spring arm 20 secured at its upper end rigidly to the 20 inner surface of post 13 as at 22, it is to be noted that the spring arm will have its innermost end rigidly secured in the slit formed in the handle post so that it may be free to be flexed and offset so as to overlie the dia- 25 metrically opposite surface of the post 13 internally thereof in a straight line, the lowermost end of this sear spring arm carrying the usual latching finger piece 19 which normally, as shown in Figure 3, projects thru slot 18 of post 13, into slot 17 of 30 umbrella handle terminal 16. Hence in the act of lowering the sleeve or handle terminal 16 in telescopic relation upon the post 13, at the proper point the latching finger 35 piece 19 will be pressed in or retracted into concealed relation in post 13 as it is obvious that the lower edge of terminal 16 riding upon the beveled edge of finger piece 19 will force it inwardly of slot 18; as soon as the slot 40 17 is reached, the finger piece will snap automatically outwardly again thus locking the terminal 16 in removable position upon this post 13. By pressing back this finger piece until it again lies concealed in post 13 as 45 shown in Figure 1, the umbrella handle can be removed from the post 13.

In practice, after the postman shall have strapped the mail bag in proper position upon his body, the clamping device can be 50 secured to the side A of bag B until it hangs erect with post 13 pointing upwardly. Then the umbrella is taken and its tubular handle latched upon post 13 in the manner described, which properly supports the umbrella covering C over the head of the postman protecting him and the contents of his mail bag from rain nuisance. I cover all changes falling within the purview of the appended claims.

What I desire to protect and seek protection on is:—

1. A bag attachment for a parasol handle consisting of a bifurcated clamp adapted to straddle a side of the bag, means on said clamp for holding said clamp against dis- 65 placement from the bag, and means carried

by the upper end of said clamp for releasably locking a parasol handle upon said clamp.

2. A device as described consisting of a bifurcated clamping member, set screws tapped into one stem of the member with its screw shanks adjustably bridging the space 70 between both stems thereof, a post rising from the top of said clamping member, and means carried by said post for locking a parasol handle thereto rigidly.

3. A device as described consisting of a bifurcated clamping member consisting of a pair of parallel arms, means engaging thru one of said parallel arms for clamping a bag between itself and the other arm of the clamping member, a post rising from the top of this clamping member, and a resilient displaceable latch carried in the post whereby to secure in removable position thereupon a parasol handle.

4. A device as described consisting of a bifurcated clamping member, a post extending from the upper end thereof, set screws tapped into one arm of the clamping member and movable in the direction of the other arm, and umbrella supporting means carried by said clamping member.

5. A device as described consisting of a clamping member formed with parallel arms, set screws tapped into one arm thereof at right angles to the latter, a post rising from the clamping member, an umbrella latch mounted yieldably in said post whereby to secure removably upon the post an umbrella handle.

6. A device as described consisting of a post, an umbrella handle securing means on said post, an under support for said post having downwardly extending parallel arms, and means carried by one arm for clamping the other arm upon the side of a flexible bag.

7. In combination a clamping member having frictional adjusting means for attaching said member upon a bag, a post on said clamping member, having a slot, a spring arm in said slot of the post carrying a latching part normally held, under the resiliency of the arm externally of said slot, and means holding said spring arm in secured position in the post.

8. A device as described consisting of means adapted to clamp opposing sides of one face of a bag, a post extending upwardly from said means, a latch projecting externally from said post, and means whereby upon back pressure exerted upon the latch same may be retracted into the post.

9. A device as described consisting of a post having means adapted to clamp removably upon one side of a bag, a handle formed with a tubular terminal telescoped upon said post, and formed with a slot, and a retractable resilient latch extending thru the side of the post and snapping automatically into the slot of the umbrella handle terminal to 130 135

secure the handle upon the post removably.

10. A device as described consisting of a U-shaped clamping device, set screws tapped into said device for securing the device in position upon a bag, a post on the device and umbrella fastening means on the post.

In witness whereof he has hereunder set his hand this fourth day of December, 1928.

JOSEPH R. DANNER.
